UNITED STATES PATENT OFFICE.

MATTHEW GRISWOLD, JR., OF ERIE, PENNSYLVANIA.

TUMBLING-MACHINE.

SPECIFICATION forming part of Letters Patent No. 695,102, dated March 11, 1902.

Application filed July 11, 1901. Serial No. 67,844. (No model.)

To all whom it may concern:

Be it known that I, MATTHEW GRISWOLD, Jr., a citizen of the United States, residing at Erie, in the county of Erie and State of Pennsylvania, have invented certain new and useful improvements in Tumbling-Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in tumbling-machines, and has for its object the construction of a tumbling-machine with a shell-retaining frame having a removable shell therein, which shell can be removed and 20 replaced by simply unbolting and removing one portion of the frame without otherwise disorganizing the mechanism thereof. I accomplish this and other objects by constructing my improved tumbling-machine substantially as hereinafter set forth and described, and illustrated in the accompanying drawings, in which—

Figure 1 is a perspective view of my improved tumbling-machine with the cover of 30 the shell-opening removed. Fig. 2 is a longitudinal section of the shell-frame with the shell and cover therein. Fig. 3 is a transverse central section of the mechanism. Fig. 4 is a plan view of the lower half-section of 35 the removable shell.

In the drawings thus illustrating my invention, A A are supporting-frames provided with shaft-bearings a a, in which hollow journals B B' are mounted, the journal B being 40 provided with tight and loose pulleys C C'. On the inner ends of the shafts B B' there are flanges or collars D, to which I bolt the ends of a connecting-frame consisting of four curved bars E, E', E², and E³, forming a skeleton frame. The bars E', E², and E³ are preferably joined together at the ends into heads F F, so that they form an integral frame joined by bolts d to the shaft-collars D D on the shafts B B'. Between the heads F F and 45 the shaft-collars D D, I secure perforated plates F', which operate as screens, through which the dust is drawn out of the shell H H',

hereinafter described, through the hollow shafts B B'. On one side of the heads F, I make a projection f, in which there is a slot f', in which the ends of the removable bar E of the frame are secured by means of bolts f². This removable bar E is provided with a central opening G, in which a removable cover G' is secured by means of a bar g and bolts 60 g' g', which cover is adapted to close a like opening h in the upper half of the removable shell H H'. This shell H H' is made preferably oval in shape and in two halves adapted to be placed together within the curved bars 65 E, E', E², and E³, which form a frame for supporting the same, the same being capable of being removed by the removal of the section E, as hereinbefore set forth, and replaced again and secured in place by replacing and 70 securing the section E of the frame in place.

To prevent the sections H H' from turning in their supporting-frame, lugs h' are cast on the outer surfaces of the sections H H' of the shell, which engage the bars E E', &c., as is 75 clearly shown in Fig. 1. To take up any lost motion caused by imperfect casting of the shell-sections H H', set-screws e are provided in the two bars E' and E³ of the shell-frame, which may be tightened up against the edges 80 of the shell-sections H H', so as to hold them firmly in place.

Among the advantages of my improved construction it will be observed that the shell-sections H H' are simple castings, upon which 85 no machine-work is necessary, and as the shell of a tumbler wears out rapidly I can make my shell-sections H H' of extremely hard castings, and they can be removed and replaced as frequently as may be necessary 90 without machine-work and without disorganizing the structure beyond the removal and replacing of the frame-section E, which may be speedily accomplished by any ordinary operative.

Having thus shown and described my invention so as to enable others to construct and use the same, what I claim as new, and desire to secure by Letters Patent of the United States, is—

1. The combination in a tumbling-machine, of a skeleton shell-frame, with removable half shell-sections therein, substantially as and for the purpose set forth.

2. The combination in a tumbling-machine of a skeleton shell-frame, a removable section in said frame, hollow shafts secured to the ends of said frame, and removable half shell-
5 sections capable of insertion into and removal from said shell-frame, substantially as and for the purpose set forth.

3. The combination in a tumbling-machine, of a frame, bearings thereon, hollow shafts
10 mounted in said bearings, flanges or collars on the inner ends of said shafts, a skeleton frame, having a removable member, secured between the flanges or collars on said shafts,

screen-plates between the ends of said frame and the collars on the shafts, a removable shell in said shell-frame, and a cover adapted to be secured to one of the skeleton frame-
15 sections, substantially as and for the purpose set forth.

In testimony whereof I affix my signature 20 in presence of two witnesses.

MATTHEW GRISWOLD, JR.
